GRINDING MACHINE

Edward Schottland, Forest Hills, N. Y., assignor of
one-half to Robert Schottland, Jackson Heights,
N. Y.

Application April 2, 1943, Serial No. 481,531

3 Claims.

(Cl. 51—263)

The present invention relates to new and useful improvements in grinding machines and more particularly it pertains to a grinding machine which employs a rotary grinding wheel to the effective surface of which a fluid abrasive is applied.

One good example of a machine of the aforementioned type is a glass grinding machine of the type employed for grinding in glass plates, shallow elongated recesses having curved bottom walls and commonly referred to in the trade as finger grips and it is in this type of machine that the present invention has been herein embodied.

Machines as generally employed for performing the above mentioned operation require two operators in attendance.

One of the operators holds the glass plate to be operated upon in grinding relation with the grinding wheel, while the other operator applies, at intervals, a fluid abrasive to the effective surface of the grinding wheel by daubing the same thereon during the grinding operation.

Such practice is expensive since it requires the efforts of two operators.

It is also inefficient, first for the reason that in daubing the abrasive upon the grinding wheel, the abrasive is not applied to the entire effective surface thereof, and second, the proportion between liquid and abrasive applied to the grinding wheel cannot be controlled, and hence, the most efficient operation of the grinding wheel does not result.

One object of the present invention is to improve the construction and mode of operation of grinding machines of the above mentioned type and to provide such machines with mechanisms which will effect a better grinding operation than any prior machines with which I am familiar.

A feature of the invention resides in the provision of a novel means for applying a fluid abrasive constantly and uniformly to the effective surface of a rotary grinding wheel during the performance of a grinding operation thereby.

The abrasive generally employed in the aforementioned operation consists of a suitable fluid, water, for example, in which the abrasive in the form of relatively heavy particles is carried in suspension and which, unless the abrasive is subjected to constant agitation, precipitate through the fluid with the result that its abrasive qualities are seriously impaired.

Another feature of the invention resides in a novel construction which functions to main-

tain a constant agitation of the abrasive while the machine is in operation; thus making possible an exact control of the abrasive mixture.

Still another feature of the invention resides in a novel construction whereby the abrasive agitating means, will, when the machine is not operating, occupy a position out of operative relation with the grinding wheel and which may be operated to move the abrasive agitating means into operative relation with the grinding wheel in which last mentioned position, a portion of the effective surface of the grinding wheel will be submerged in the abrasive.

This last mentioned feature is important since it assures uniform application of the abrasive to the entire effective surface of the grinding wheel thereby materially reducing the grinding period and consequently increasing the efficiency of the machine.

Other features of the invention relate to certain novel and improved constructions, arrangements and combinations of parts hereinafter described and particularly pointed out in the claims, the advantages of which will be readily understood and appreciated by those skilled in the art.

The invention will be understood from the accompanying drawings illustrating the invention in its preferred form and the following description of the constructions therein shown.

In the drawings,
Figure 1 is a view in side elevation illustrating a machine embodying the present invention,
Figure 2 is a top plan view thereof.

Figure 3 is a view in front elevation, thereof,
Figure 4 is a fragmentary vertical sectional view taken substantially on the line 4—4 of Figure 1, looking in the direction of the arrows,
Figure 5 is a vertical sectional view taken substantially on the line 5—5 of Figure 3, and;

Figure 6 is a detail sectional view of a portion of the machine illustrating the grinding wheel and the abrasive receptacle and their relation to each other.

Referring to the drawings by reference character, 10 designates a frame, which comprises a substantially rectangular main body portion 11 having spaced upstanding arms 12 extending from the upper side edges of the frame at the forward portion thereof.

These arms are provided on their upper ends with bearings 13 which support a shaft 14 upon which is mounted a grinding wheel 15.

Referring to Figure 3, it will be noted that the right hand end of the shaft 14 is extended

and carries a pulley 16, around which passes a driving belt 17 for driving the pulley 16, the shaft 14, and the grinding wheel 15.

Extending rearwardly from the frame 10 are two spaced arms 18. These arms 18 carry bearings 19 and adjacent said arms there is a motor 20 around a driving pulley 21 of which the belt 17, heretofore mentioned, passes.

Mounted in the bearings 19 and pivotally connected with the armature shaft of the motor 20 there is a shaft 22 and keyed to said shaft 22 and disposed between the arms 18, heretofore mentioned, there is a driving worm 23.

The reference character 25 designates a second frame which comprises a main body portion 26 having an angular extension 27 from which extends a right angular extension 27'.

The frame 25 is mounted upon the shaft 22, heretofore mentioned, in a manner which will permit of a slight pivotal movement about the shaft, which construction is provided for a purpose which will be hereinafter more specifically described. For mounting the frame 25 upon the shaft 22 yoke members 28 extend from the underside of the main body portion 26 of the frame which yoke members carry bearings through which the shaft 22 passes.

The frame 25 occupies a position in a plane at an angle of approximately 45° to the vertical. This frame is adapted for adjustment relative to the grinding wheel and the frame 10 by rocking it about the shaft 22 and it is mounted rigidly in its adjusted position preferably by means of three bolts 29, 29', and 30.

The two bolts 29 and 29' have threaded engagement with the stationary frame 10, each being loosely mounted in the angular extension 27 of the frame 25; one of which bolts is illustrated in Figure 5. The bolt 30 has threaded engagement with the stationary frame 10 and its free end engages the underside of the angular extension 27 of the frame 25 as at 30' in Figure 5.

By this construction, the bolt 30 forms a stop to position the frame 25, while the bolts 29 and 29' serve to retain the frame 25 in rigid engagement with the stop 30 when said bolts are tightened, thus providing means for adjusting the frame 25 relative to the frame 10 and the grinding wheel.

Upon the lower end of the body portion 26 of the frame 25 there are two spaced bearings 31. These bearings support the lower end of a shaft 32, the opposite end of which is supported in a bearing 33 at the upper end of the body portion 26 of the frame 25, and, as best illustrated in Figure 5, a portion 34 of the shaft 32 extends beyond the upper bearing 33, heretofore mentioned.

Mounted upon the shaft 32 between the bearings 31 there is a worm gear 35 which meshes with the driving worm 23, heretofore mentioned. The worm gear 35 is keyed to the shaft 32 in such a manner that the shaft may have sliding movement in the hub portion 36 of the worm gear and at the same time establish a driving connection between the worm gear 35 and the shaft 32.

The reference character 37 designates a thrust bearing preferably of the roller bearing type which is carried by the shaft 32 and keyed thereto as indicated at 38 in Figure 5 of the drawings. The thrust bearing 37 is slightly spaced with respect to the bearing 31 and slidably mounted upon the shaft and upon the body portion 26 of the frame 25 between the bearing 31 and said thrust bearing, there is a shoe or the like 38'.

The shoe 38' is moved longitudinally of the

shaft 32 by means of cables, cords or the like 39, which are connected to the shoe as at 40 at opposite sides thereof as best illustrated in Figures 1 and 2.

These cords or cables 39 pass over pulleys 41 carried by the body portion 26 of the frame 25 and they are connected to a cross member 42 which in turn is connected by means of a suitable pull cable or the like 43 with an arcuate member 44, see Figures 3 and 4, which arcuate member is keyed to a tubular shaft 45, see Figure 5, mounted in the lower portion of the frame 10. The shaft 45 carries a foot lever 46 for rocking the shaft 45 to in turn rock the arcuate member 44 to exert a downward pull upon the connecting member 43, to operate the pull cables or cords 39 to move the shoe 38' upwardly of the frame 25 thereby to slide the shaft 32 in its bearings 31 and 33 through the medium of the thrust bearing 37, heretofore mentioned.

Thus, it will be apparent that when the operator applies pressure to the foot lever 46, the tubular shaft 45 will be partially rotated and it will partially rotate the arcuate member 44 to exert a pull upon the connecting cables or cords 43 and 39 to impart a sliding movement to the shaft 32.

The reference numeral 47 designates a weight which may be carried by the cross member 42 and which serves to partially counter balance the weight of the shaft 32, the shoe 38', the thrust bearing 37 and other elements associated with the shaft 32 in order to minimize the effort required to slide the shaft 32 in its bearings.

The reference character 50 designates a receptacle for containing an abrasive material or an abrasive element which consists of a suitable fluid adapted to carry a suitable abrasive material in suspension therein during a grinding operation.

The abrasive receptacle 50 has a main body portion 51 of substantially inverted frusto-conical shape from the peripheral edge of which projects a continuous flange 52.

This receptacle is best illustrated in Figure 6 of the drawings and by reference to said figure it will be noted that it is provided with a socket member 53 for receiving the extended end 34, heretofore mentioned, of the shaft 32 to which it is keyed or operatively connected by a cross key 54.

The several parts thus far described are so proportioned and positioned that the abrasive receptacle when in position upon the upper end of the shaft will enclose or receive a portion of the grinding wheel as best illustrated in Figures 5 and 6.

In addition to the abrasive receptacle, the grinding wheel 15 is partially enclosed by two hoods or guards 55 and 56, both of which extend partially into the open end of the abrasive receptacle as best illustrated in Figure 6. The hood or guard 55 is both transversely and longitudinally curved and encloses a portion of the upper portion of the grinding wheel 15 and it is connected rigidly to the upper ends of the arms 12 of the frame 10 by means of plates or the like 58, which plates serve to hold the hood or guard rigidly in position. The hood or guard 56 partially encloses the forward lower portion of the grinding wheel 15 and this hood or guard is rigidly carried by the upper end of the right angular extension 27' of the frame 25.

Referring to Figure 6, it will be apparent that the hood or guard is so shaped and proportioned that its main body portion 56' occupies a position relatively close to the adjacent wall 57' of the

abrasive receptacle 50 and it is of such length as to extend well into the abrasive material during operation of the machine.

By thus constructing the hood or guard 56 it acts also as a baffle in the path of the revolving abrasive material and serves to break up the centrifugal action upon the abrasive material at the lowest point of the abrasive receptacle, thus preventing discharge of abrasive during rotation of the receptacle.

The abrasive element is preferably employed in such a quantity that when the machine is at rest, the level thereof will be below the lowest point of the grinding wheel. This position of the parts is illustrated in Figure 5 of the drawings.

When it is desired to perform a grinding operation, the motor 20 is started whereupon the grinding wheel 15 will be driven through the medium of the belt 17 in the manner heretofore described and the shaft 32 will be rotated through the medium of the driving worm 23 and the worm gear 35. Since the abrasive receptacle 50 is carried by the shaft 32, the rotary movement of said shaft will also impart a rotary motion to said receptacle which motion will produce a swirling action of the abrasive material within the receptacle 50 thereby to agitate the same and maintain the particles of the abrasive contained therein in suspension in the fluid as long as the rotating motion of the receptacle 50 is maintained.

With the parts operating the positions just described, the operator exerts pressure upon the foot lever 46 to reciprocate the shaft 32 in its bearings 31 and 33 in the manner heretofore described, which action slides the shaft 32 in its bearings 31 and 33 to move the abrasive receptacle in the direction of the grinding wheel 15 to the position where the lower portion of the grinding wheel will be immersed in the abrasive element to a sufficient depth to pick up the required amount of abrasive material to perform a grinding operation.

With the machine operating as thus far described, the operator positions a glass plate, such as designated A in Figure 6, engaging the face thereof with the grinding wheel 15 to form the so-called finger grip recess in the plate. Merely by imparting a reciprocating movement to the plate A, the recess ground therein may be made of any desired length.

Means is provided to retain the abrasive receptacle in elevated or operative position with respect to the grinding wheel and this means includes a shaft 60, see Figure 5, mounted within the tubular shaft 45, heretofore mentioned. On its forward end, the shaft 60 carries a foot lever 61. Upon its rear extremity, it carries a lever 62 which is connected by means of a spring 63 to the frame 10. The reference character 64 designates a pawl which is pivotally connected as at 65 in an arm 66 extending from the stationary frame 10. Attached to the pawl 64 there is an arm or lever 67 which is connected with the lever 62 by means of a rod 68. The pawl 64 is adapted to engage a lug 70 upon the curved face of the arcuate member 44 when the same is rocked in the downward direction to elevate the shaft 32 and the abrasive receptacle 50 in the manner heretofore described.

The pawl is normally held in constant engagement with the curved face of the arcuate member by the spring 63 whereupon the engagement of

the pawl 64 with the lug 70 is automatic upon rocking of the arcuate member 44 in the downward direction.

To release the holding engagement of the pawl 64, pressure is applied to the foot lever 61 which rocks the shaft 60 to the right in Figure 4 against the tension of the spring 63. Through the medium of the rod 68 and the arm or lever 67, the pawl 64 will be rocked out of engagement with the lug 70 permitting the arcuate member 44 to rock in an upward direction and move the shaft 32 and the abrasive receptacle to their normal positions under the influence of gravity.

From the foregoing, it will be apparent that the present invention provides a machine in which the desired grinding operation may be expeditiously carried out.

Furthermore, the invention provides for constant agitation of the abrasive material and its constant and uniform application to the grinding wheel in a manner which permits of efficient operation of the machine with but a single attendant or operator.

Having thus described the invention, what is claimed as new is:

1. A machine of the type described comprising in combination, a stationary frame, a grinding wheel mounted for rotation in a fixed position on said frame, means for driving said grinding wheel, a second frame pivotally mounted upon the first mentioned frame, a shaft slidably mounted in said second mentioned frame and disposed thereon at an angle to the vertical, an abrasive receptacle carried by the upper end of said shaft, said abrasive receptacle partially enclosing the grinding wheel, means for driving said shaft to impart an agitating motion to the abrasive receptacle, means for sliding said shaft upon the second mentioned frame to move the abrasive receptacle into operative relation with the grinding wheel, and means for maintaining the abrasive receptacle in operative relation with the grinding wheel.

2. A machine of the type described comprising in combination, a stationary frame, a grinding wheel mounted for rotation in a fixed position on said frame, means for driving said grinding wheel, a second frame carried by the stationary frame, an abrasive receptacle, means for slidably mounting the abrasive receptacle upon the second mentioned frame, means for rotating the abrasive receptacle to impart an agitating action thereto, and means for moving the abrasive receptacle into and out of operative relation with the grinding wheel.

3. A machine of the type described comprising in combination, a stationary frame, a grinding wheel mounted for rotation in a fixed position on said stationary frame, means for driving said grinding wheel, a second frame, means for pivotally mounting the second mentioned frame upon the stationary frame to provide for its adjustment relative thereto, a shaft, means for mounting the shaft for sliding and rotating movement upon the second mentioned frame, an abrasive receptacle carried by said shaft, means for rotating said shaft to impart an agitating action to the abrasive receptacle, and means for reciprocating said shaft to move the abrasive receptacle into and out of operative position relative to the grinding wheel.

EDWARD SCHOTTLAND.
